BURNER CONTROL

William F. Wolfner, II, Methuen, Mass., assignor
to Photoswitch Incorporated, Cambridge, Mass.,
a corporation of Massachusetts

Application October 16, 1941, Serial No. 415,257

10 Claims. (Cl. 122—504)

This invention relates to the control of burners, especially of the type used with home heating plants remotely controlled by a thermostat and provided with automatic supervisory equipment which permits operation of the plant with a maximum of safety and convenience.

It is one of the main objects of the invention to provide an installation of this type which provides a flame failure safeguard that operates with absolute certainty and safety and independently of any apparatus mounted on boiler or flue. Other objects are to provide a burner control which reacts instantaneously to conditions which it is to supervise, to provide a control suited for direct cooperation in a simple and therefore reliable manner with other supervisory equipment such as a water level gauge; and to provide a complete burner control which is an integral part of the heating system and can be installed and tested with a minimum of effort.

These and other objects and aspects of the invention will be apparent from the following description of a practical embodiment illustrating its genus. The description refers to drawings, in which

Fig. 1 is a schematical representation of an oil burner equipment according to the invention;

Fig. 2 is a simplified diagram of the circuit of Fig. 1;

Fig. 3 is a top elevation of the control apparatus according to Fig. 1; and

Fig. 4 is a side elevation of the apparatus according to Fig. 3, with part of the oil burner and the apparatus housing in vertical section.

The boiler indicated at *b* of Fig. 1 is equipped with an oil burner *h* of the customary type, and a combustion initiating and sustaining means such as the usual electric ignition device *i* and electro-motor *m*. A phototube *P* constituting a detecting means is mounted on the burner, as shown in detail in Figs. 3 and 4, in such a manner that it receives radiation from the heating flame when the burner is in operation.

The boiler may be equipped with a water level supervisor *L* consisting of a probe *l* extending at the height of the lowest permissible water level through an insulating bushing into boiler *b* and closing a circuit to ground so long as the water level is above the probe.

The heater equipment further comprises a temperature detecting device such as thermostat *S* of usual design, closing a circuit (Fig. 2) when its ambient temperature reaches a certain value. The thermostat may be of the so-called three wire

type with an additional contact whose connection will be described below.

The electric equipment, preferably mounted within a single housing together with the phototube *P*, as shown in Figs. 3 and 4, is supplied from an alternating current source indicated by terminals *1*, *2* which feed into a transformer *3* with primary *4* and secondary *5*, the latter having several taps *O*, *I*, *II*, *III* from which are derived potentials appropriate for the various components of the circuit.

An electronic tube *T* for example of the cold cathode type with cathode *k*, anode *a* and starting anode *g* is connected between transformer terminal *O* and tap *III*; in series in the cathode connection are starting contacts *11* and *12* of thermostat *S* and in series in the anode connection is tube relay magnet *B* controlling normally open shunting switch *B₁* and normally closed ignition switch *B₂*, which latter is inserted in series to *i* only if intermittent ignition control is provided.

An actuating magnet *A* or other suitable relay means is connected to cathode *k* and controls two normally open switches, namely, motor switch *A₁* and heater holding or shunting switch *A₂*. Magnet *A* is preferably so dimensioned that it will operate its switches only if supplied with the proper line voltage. Switches *A₂* and *B₁* provide a holding circuit for magnet *A* when contacts *C₁* and *C₂* are opened.

To tap *I* is connected a thermal switch *W* whose mechanical construction will be explained in detail below and which has two bimetallic temperature responsive actuator elements *21*, *22*, which are associated with resistances constituting main heater winding *C* providing a priming timer, and auxiliary heater winding *D* providing a safety timer, respectively, and three switches *C₁*, *C₂* and *D₁* herein also referred to as priming and safety switches, respectively.

The main heater or priming switches *C₁* and *C₂* are normally retained closed by strip *21* but will open, with *C₁* opening before *C₂*, when strip *21* is sufficiently heated by current flowing through heater *C*. The two heaters are so dimensioned that *D* has a higher resistance and heats up faster than *C*.

Strip *22*, which moves perpendicularly to *21* (normally to the drawing surface of Figs. 1 and 4), controls safety switch *D₁*, which opens as soon as insulation lug *24* has passed spring *25* of switch *D₁* in its movement lateral to that spring. The heater strip *22* is then retained in deflected position by spring *25*, even if tending to return to

normal unheated position, unless released by push button 30 (Fig. 4) which, upon being pressed, first moves both springs 25 and 26 inwardly while keeping them apart, whereupon strip 22 is permitted to snap back into normal unheated position. Release of button 30 then effects reclosure of switch D1 through contact of springs 25 and 26.

As shown in Fig. 2, switch D1, C1, C2, heater D, heater C and magnet A are connected in series between tap I and cathode k, which may be grounded, whereas heater switch A2 is connected in parallel to switch C1 and shunting switch B1 in parallel to switch C2.

If a liquid level probe L is used, it is connected between cathode k and the thermal switch W through primary 41 of a booster transformer 40, whose secondary 42 is connected to tap II of the main transformer. It will be noted that, due to this arrangement, it is possible to comply with the requirement that probes of this type carry only low voltage.

The phototube P is with its anode a connected to starting electrode g of tube T and with its cathode k to tap III or, if a level probe is used, the booster secondary 42. In the latter case, connection 45 is opened whereas, if the level probe is not used, connections 46 and 47 are opened, with 45 closed. A condenser 50 is connected between electrode g and cathode k.

Figs. 3 and 4 show the mechanical arrangement of the above-described circuit. The thermal switch W is shown in Fig. 4, which indicates that push button bar 30 has two abutments 51, 52 whose distance is greater than that of switch springs 25, 26 and which control switches C1, C2 and heater strip 22, as above described. Figs. 3 and 4 further indicate that, according to the invention, the phototube T is mounted within a hood 55 fastened with clips 56 to base plate 57. This construction permits removal of housing 58 from base plate 57 and burner casting 59 without exposing the phototube to light in case it is desired to inspect the installation in operative condition.

Figs. 3 and 4 further indicate terminal block 60 and bushings 61, 62 for the ignition leads, as well as oil supply tube 63. The wiring connections are arranged as far as possible below base plate 57, and it will be apparent that the herein described preferred construction is especially compact and convenient, eliminating a good deal of the wire connections and separately mounted circuit elements of conventional constructions.

The above-described arrangement operates as follows:

Under normal idling conditions with the burner cold, the controlling temperature above the critical value and the water level normal, the circuit elements are conditioned as indicated in Figs. 1 and 2.

If the thermostat contacts 11, 12 are now closed either by hand or due to the controlling temperature falling below the desired level, magnet A is energized through circuit

I—D1—C1—C2—D—C—A—12—11—O

Magnet A closes switches A1 and A2, starting motor and ignition through circuit I—A1—m—2 and I—A1—i—B2—2, and preparing a circuit directly including heater C and excluding heater D, through

I—D1—A2—B1—C—A—S—O

Heaters C and D are now heating up, and D be-

ing, as above described, of higher resistance than C, heats up faster than C.

The ignition being effective, the burner flame starts and the phototube receives light from the burner flame so that its impedance is considerably lowered, which causes the potential at the electrode g to rise above the starting value; tube T becomes conductive and magnet B is energized.

Magnet B now closes switch B1, shunting out through the above-traced circuit heater D which normally will not yet have reached a position permitting opening of switch D1, and therefore causing heater C to heat up more rapidly. If intermittent ignition control with switch B2 is provided, magnet B also opens B2, thereby cutting out ignition device i.

Heater C quickly continues to heat its bimetallic strip which, after a predetermined time, opens first switch C1 and then switch C2.

The burner is now in normal operating condition, with phototube P illuminated, with control tube T conducting and magnet B energized, and with magnet A and heater C energized in the direct circuit I—D1—A2—B1—C—A—S—O.

It will be observed that magnet A and hence motor m and ignition device i remain energized until switch C2 opens, regardless of the fact whether or not the flame starts and causes switch B1 to be closed, and whether switch C1, at that time already shunted by A2, has opened. This arrangement assures a proper "cold" priming period for starting when heaters C and D are cold.

If thermostat shut-off is effected by the rise of room temperature during normal operation of the burner, the opening of contacts 11, 12 de-energizes magnet A and stops the motor, and darkening of the phototube restores the entire circuit to normal idling condition.

If a person should raise the thermostat setting immediately after normal thermostat shut-off, the burner will not restart immediately but pause for a scavenging period, due to the fact that heater C has to cool down before switches C1 and C2 are again closed in readiness for starting through energization of magnet A. Similarly, if the burner is normally running and a person shuts it off momentarily with the thermostat, immediately raising the thermostat setting again, the scavenging period will always be completed before starting is permitted, for the above reasons.

If ignition failure should occur, that is, if the burner flame should fail to start although the ignition device is effective, the photocell will fail to render tube T conductive and magnet B will not be energized, so that B1 fails to shunt out heater D. Heater strip 22, after a predetermined time, will permit switch D1 to open, which deenergizes the circuit of magnet A and opens switch A1, stopping motor and ignition. Both heater coils C and D will now cool off, since their circuits are interrupted at D1; switches C1 and C2 will stay closed, but switch D1 will remain open due to the above-described mechanical correlation of heater strip 22 and switch spring 25. Therefore all elements excepting D1 are in position for starting, so that the burner can now be restarted by releasing starter button 30 after it has been depressed. It will be noted that the burner cannot be started or kept running by keeping button 30 in depressed position; only release of the button 30 initiates the starting cycle.

If flame failure should occur, that is, if the

burner flame fails to start, the photocell will fail to render tube T conductive and magnet B will not be energized, so that B1 fails to shunt out heater D. Heater strip 22, after a predetermined time, will permit switch D1 to open, which deenergizes the circuit of magnet A and opens switch A1, stopping motor and ignition. Both heater coils C and D will now cool off, since their circuits are interrupted at D1; switches C1 and C2 will stay closed, but switch D1 will remain open due to the above-described mechanical correlation of heater strip 22 and switch spring 25. Therefore all elements excepting D1 are in position for starting, so that the burner can now be restarted by releasing starter button 30 after it has been depressed. It will be noted that the burner cannot be started or kept running by keeping button 30 in depressed position; only release of the button 30 initiates the starting cycle.

If flame failure should occur, that is, if the

flame should become extinguished after having been properly ignited, phototube P becomes dark, magnet B is deenergized and switch B1 opens. Switch B2, if provided, closes. Switch B1 opens the energizing circuit of magnet A and coil C under "normal operating conditions," namely, I—D1—A2—B1—C—A—S—O and magnet A releases switches A1 and A2; switch A1 stops the motor. Heater coil C cools and, after a predetermined time, closes first switch C2 and then switch C1, due to the above-described construction of these switches. During a scavenging period which terminates when switch C1 closes, starting is impossible since, although C2 is closed, A2 has opened with magnet A becoming deenergized. Switch D1 being still closed since D was cool because C2 was open, and assuming that 11 and 12 remain closed, magnet A becomes again energized and starts ignition and motor so that normal operation may begin, provided proper combustion is possible; if the fuel should fail to ignite, the condition explained above under "ignition failure" prevails and the circuit will perform the operations described under that heading. It will be observed that in this case also a priming period is provided, which lasts from the end of the scavenging period or the energization of A until C2 opens.

If power supply failure should occur, relay A becomes deenergized for lack of potential supplied thereto and the motor will stop. Heater coil C becomes likewise deenergized and switches C1 and C2 will close after a predetermined time corresponding to the cooling period of strip C. Closing of switches C1 and C2 reenergizes coils D and C and magnet A and normal operation will begin provided that power supply has been resumed during the cooling of strip C.

In case of oil failure, extinction of the flame causes magnet B to become deenergized, whereupon magnet A also becomes deenergized, A1 and A2 open, C cools, C2 closes, and C1 closes, terminating the scavenging period. With the closing of C1, heater D begins to deflect and in due time permits safety switch D1 to open, with all other elements in position for starting as described above with reference to ignition failure.

In case of parts failure, that is, if any one of the electric current elements of the apparatus should become defective, the circuit energizing magnet A becomes necessarily deenergized and the burner is shut down or prevented from starting; it will now be apparent that this response is inherent in the circuit according to the invention, since the elements sustaining normal operation, namely, magnets A and B and heater coils C and D, are energized during, and have to be in good condition for such operation, so that any failure affecting these essential elements will stop operation.

If water failure should occur, that is, if contacts 43 44 (Fig. 2) should be interrupted due to the water level falling below probe L, the circuit ground—I—D1—A1—L—ground—O is interrupted and the potential difference supplied by secondary 42, retaining electrode g at starting level, is eliminated. The windings of transformer 40 are so arranged that the voltage across secondary 42 lifts the potential of electrode g above the starting value if phototube P is illuminated and the water level above probe L, but that electrode g goes below the starting potential level if either phototube P becomes dark or the water level falls below the probe. There-

fore tube T becomes non-conductive and magnet B deenergized if water failure occurs, switch B1 opens, and the circuit operates as described above under the heading "flame failure."

It will now be understood that operation without water level supervision can be provided by connecting the phototube P directly to tap III through jumper 45, the booster arrangement being rendered ineffective by opening jumpers 46 and 47. The booster voltage will be so chosen that the potential level of electrode g is the same whether supplied through transformer 40 or directly from tap III; in other words, the potential difference at secondary 42 corresponds to that between taps II and III, provided of course that, as indicated above, these values are so chosen that either darkening of the phototube or elimination of the effect of primary 41 brings the potential of the auxiliary anode g below the value which renders the tube conductive.

It will be evident that hot cathode electron tubes can be used analogously if operating conditions similar to those above described are provided. The term "triode" as herein used includes high vacuum as well as gas tubes with at least three electrodes including a control electrode.

If a so-called three-wire thermostat is used, that is, a thermostat which has an auxiliary resistor which heats the thermostat proper independently of the room temperature, the third wire containing this resistor is provided with a normally open switch A3 controlled by magnet A similarly to motor switch A1, as indicated in Figs. 1 and 2.

It should be understood that the present disclosure is for the purpose of illustration only and that this invention includes all modifications and equivalents which fall within the scope of the appended claims.

I claim,

1. In heating plant control apparatus of the type described, the combination of a current source, a combustion burner, means for initiating and sustaining periods of heating by said burner, and detecting means distinguishing between heating and nonheating periods of said plant, with an actuating circuit including in direct series connection a priming timer, a safety timer, normally closed priming switch means, said priming switch means being arranged to be opened and reclosed by said priming timer after a first predetermined period from energization and deenergization of said circuit, respectively, and a normally closed safety switch arranged to be opened by said safety timer after a second predetermined period from said energization; relay means for actuating said sustaining means upon energization of said circuit; and shunting switch means in parallel to said safety timer and said priming switch means and arranged to be closed by said detecting means upon beginning and opened upon termination of a heating period; said safety timer deenergizing said actuating circuit by opening said safety switch after said second period upon failure of said detecting means to close said shunting switch means, and said priming timer establishing said actuating circuit solely through said shunting switch means by opening said priming switch means and reestablishing normal condition by closing said priming switch means, after said first periods.
2. In heating plant control apparatus of the

type described, the combination of a current source, a combustion burner, means for initiating and sustaining periods of heating by said burner, and detecting means distinguishing between heating and nonheating periods of said plant, with an actuating circuit including in direct series connection a priming timer a safety timer a normally closed priming switch a normally closed second priming switch, said priming switches being arranged to be opened and reclosed by said priming timer after a first predetermined period from energization and deenergization of said circuit, respectively, with said second priming switch opening somewhat prior to and closing somewhat after said first priming switch, and a normally closed safety switch arranged to be opened by said safety timer after a second predetermined period from said energization; relay means for actuating said sustaining means upon energization of said circuit; and shunting switch means in parallel to said safety timer and said priming switches and arranged to be closed by said detecting means upon beginning and opened upon termination of a heating period; said safety timer deenergizing said actuating circuit by opening said safety switch after said second period upon failure of said detecting means to close said shunting switch means, said priming timer establishing said actuating circuit solely through said shunting switch means by opening said priming switches and reestablishing normal condition by closing said priming switches after said first periods, and said delayed closing of said second priming switch securing a scavenging period upon initiation of a heating period while said priming timer is in switch opening condition.

3. In heating plant control apparatus of the type described, the combination of a current source, a combustion burner, means for initiating and sustaining periods of heating by said burner, and detecting means distinguishing between heating and nonheating periods of said plant, with an actuating circuit including in direct series connection a priming timer, a safety timer, normally closed priming switch means, said priming switch means being arranged to be opened and reclosed by said priming timer after a first predetermined period from energization and deenergization of said circuit, respectively, and a normally closed safety switch arranged to be opened by said safety timer after a second predetermined period from said energization; relay means for actuating said sustaining means upon energization of said circuit; and shunting switch means in parallel to said safety timer and said priming switch means and arranged to be closed by said detecting means upon beginning and opened upon termination of a heating period, said timers being so arranged that said second period is shorter than said first period when said shunting switch is open whereas closing of said shunting switch renders said second period longer than said first period; said safety timer deenergizing said actuating circuit by opening said safety switch after said second period upon failure of said detecting means to close said shunting switch means, and said priming timer establishing said actuating circuit solely through said shunting switch means by opening said priming switch means and reestablishing normal condition by closing said priming switch means after said first periods.

4. In heating plant control apparatus of the type described, the combination of a current

source, a combustion burner, means for initiating and sustaining periods of heating by said burner, and detecting means distinguishing between heating and nonheating periods of said plant, with an actuating circuit including in direct series connection a priming timer, a safety timer, a normally closed priming switch, a normally closed second priming switch, said priming switches being arranged to be opened and reclosed by said priming timer after a first predetermined period from energization and deenergization of said circuit, respectively, with said second priming switch opening somewhat prior to and closing somewhat after said first priming switch, and a normally closed safety switch arranged to be opened by said safety timer after a second predetermined period from said energization; relay means for actuating said sustaining means upon energization of said circuit; a normally open presetting switch in parallel to said second priming switch and arranged to be closed upon said energization of the actuating circuit; and a shunting switch in parallel to said safety timer and said first priming switch and arranged to be closed by said detecting means upon beginning and opened upon termination of a heating period, the closing of said shunting switch causing deenergization of said safety timer and hence increased current supply and more rapid operation of said priming timer with shortening of said first period to less than said second period prior to the opening of said priming switches; said safety timer deenergizing said actuating circuit by opening said safety switch after said second period upon failure of said detecting means to close said shunting switch, said priming timer establishing said actuating circuit solely through said holding and shunting switches by opening said priming switches and reestablishing normal condition by closing said priming switches after said first periods, and said delayed closing of said second priming switch securing a scavenging period upon initiation of a heating period while said priming timer is in switch opening condition.

5. In heating plant control apparatus of the type described, the combination of a current source, a combustion burner, means for initiating and sustaining periods of heating by said burner, and detecting means distinguishing between heating and nonheating periods of said plant, with an actuating circuit including in direct series connection relay means for actuating said sustaining means upon energization of said circuit, a priming timer, a safety timer, a normally closed priming switch, a normally closed second priming switch, said priming switches being arranged to be opened and reclosed by said priming timer after a first predetermined period from energization and deenergization of said circuit, respectively, with said second priming switch opening somewhat prior to and closing somewhat after said first priming switch, and a normally closed safety switch arranged to be opened by said safety timer after a second predetermined period from said energization; a normally open holding switch in parallel to said second priming switch and arranged to be closed upon said energization; and a shunting switch in parallel to said safety timer and said first priming switch and arranged to be closed by said detecting means upon beginning and opened upon termination of a heating period, said timers being so arranged that said second period is shorter than said first period when said shunting switch

is open whereas closing of said shunting switch renders said second period longer than said first period; said safety timer deenergizing said actuating circuit by opening said safety switch after said second period upon failure of said detecting means to close said shunting switch, said priming timer establishing said actuating circuit solely through said holding and shunting switches by opening said priming switches and reestablishing normal condition by closing said priming switches 10 after said first periods, and said delayed closing of said second priming switch securing a scavenging period upon initiation of a heating period while said priming timer is in switch opening condition.

6. In heating plant control apparatus of the type described, the combination of a current source, a combustion burner, means for initiating and sustaining periods of heating by said burner, and detecting means distinguishing between heating and nonheating periods of said plant, with a priming unit including a thermo-responsive actuator, a resistance in heat conductive relation with said actuator, a first and second priming switch which priming switches are normally retained closed by said actuator which, after a predetermined period from energization and hence heating of said resistance opens said second and shortly thereafter said first priming switch and which actuator after a predetermined period from deenergization and hence cooling of said resistance closes said first and shortly thereafter said second priming switch; a safety timer; a normally closed safety switch arranged to be opened by said safety timer after a second predetermined period from said energization; said resistance, said safety timer, said priming switches and said safety switch being connected directly in series and constituting an actuating circuit; relay means for actuating said sustaining means upon energization of said circuit; and shunting switch means in parallel to said safety timer and said priming switches and arranged to be closed by said detecting means upon beginning and opened upon termination of a heating period; said safety timer deenergizing said actuating circuit by opening said safety switch after said second period upon failure of said detecting means to close said shunting switch means, said priming unit establishing said actuating circuit solely through said shunting switch means by opening said priming switches and reestablishing normal condition by closing said priming switches after said first periods, and said delayed closing of said second priming switch securing a scavenging period upon initiation of a heating period while said actuator is in switch opening condition.

7. In a heating plant, comprising a boiler, a burner device for heating said boiler that is served by a combustion sustaining motor and supervised by a water probe on said boiler and a control thermostat; a current source; a phototube adapted to receive radiation from the flame of said burner; an electron discharge device having at least a control electrode and an anode and cathode connected to said source; means for connecting said phototube between said control electrode and said source for applying to said electrode through the phototube, while its conductivity is increased through radiation from said flame, a potential rendering the discharge device conductive; means controlled by said probe for lowering said potential sufficiently to render said discharge device non-conductive; relay 75

means in the anode circuit of said discharge device; and an actuating circuit adapted to be energized from said source by said thermostat and including means for starting said motor upon energization of the actuating circuit, an actuator responsive to temperature increase, switching means controlled by said relay means for heating said actuator when the discharge device is non-conductive and the actuating circuit energized, and a normally closed circuit breaker controlled by said actuator to deenergize said actuating circuit upon heating of said actuator.

8. In a heating plant, comprising a boiler, a burner device for heating said boiler that is served by a combustion sustaining motor and an electric ignition device and supervised by a water probe on said boiler and a control thermostat; a current source; an electron discharge device having at least a control electrode and an anode and cathode connected to said source, a relay magnet in the anode circuit of said discharge device; a potential divider connected to said source; a phototube adapted to receive radiation from the flame of said burner; a connection from a point of intermediate potential of said divider through said phototube to said control electrode and containing a transformer secondary for applying to said electrode through the phototube and the secondary a potential controlled by the impedances of said phototube and said secondary; a condenser between said control electrode and said cathode; a switch adapted to be closed by said relay magnet for energizing said ignition device upon said discharge device becoming conductive; an actuating circuit including in series a manually controllable resetting switch connecting to a point of lower potential of said divider, two safety switches, a temperature responsive resetting switch actuator normally holding said resetting switch closed, a temperature responsive safety switch actuator normally retaining said safety switches closed and a magnet for starting said motor connecting to said cathode, and in parallel to one of said safety switches a holding switch controlled by said starting magnet and in parallel to the second safety switch a shunting switch controlled by said relay magnet; a connection between a point of lowest potential of said divider and said cathode and containing said control thermostat; and a connection between said resetting switch and said cathode containing said probe and a transformer primary coupled to said transformer secondary.

9. Electronic control apparatus providing response of a single electron discharge device to two irregularly varying conditions supervised by two independent detecting elements, comprising an alternating current source; an electron discharge device having an input circuit and an output circuit supplied from said source; means responsive to conductivity changes of said discharge device; a first control circuit adapted to apply between said input and output circuits a control potential and including a first detecting element having an impedance varying with said first condition and an inductance; and a second control circuit including a second inductance which is coupled to said first inductance, and a second detecting element adapted to vary the current in said second inductance in accordance with said second condition; the conductivity of said discharge device changing with the change of control potential due to variation of the impedance of said first detecting element as well as with the

potential drop across said inductances as affected by said second detecting element.

10. Electronic control apparatus comprising an alternating current source; an electron discharge device whose anode circuit is supplied from said source; current responsive means in said anode circuit; a first control circuit adapted to apply to the control electrode of said discharge device a control potential derived from said source and including a phototube constituting a light detecting element and a transformer secondary; and a second control circuit deriving a potential differ-

ence from said source and including a transformer primary coupled to said secondary and current control means constituting a second detecting element adapted to vary the current flow in said primary and hence the potential drop in said secondary; the control potential applied to said electrode and hence the conductivity of said discharge device being controllable by the light flux on said phototube as well as by the potential drop across said secondary as affected by said second detecting element.

WILLIAM F. WOLFNER, II.
